[57] CLAIM

The ornamental design for a stand-alone drive for disk-shaped data storage media, as shown and described.

DESCRIPTION

FIG. 1 is a front isometric view of a stand-alone drive for disk-shaped data storage media according to the present invention;

FIG. 2 is a top view of the drive shown in FIG. 1;
FIG. 3 is a bottom view of the drive shown in FIG. 1;
FIG. 4 is a side view of the drive shown in FIG. 1; the opposite side view is identical;

FIG. 5 is a front view of the drive shown in FIG. 1; and,
FIG. 6 is a rear view of the drive shown in FIG. 1.
The circular elements in FIG. 5 and the portions of the disk cartridge in FIG. 6 are shown in broken lines for illustrative purposes only and form no part of the claimed design.
